TOOL FOR INSTALLING VALVE STEM GUIDE
BUSHINGS

Gerald H. Birk, San Jose, Calif.

Application March 3, 1947, Serial No. 731,935

5 Claims. (Cl. 29—275)

1

The present invention relates to a tool for installing valve stem guide bushings in the cylinder block of internal combustion engines or the like.

One object of the present invention is to provide a tool for installing valve stem guide bushings in predetermined position in the cylinder block of an engine.

Another object is to provide a tool for installing valve stem guide bushings in the cylinder block of an engine in predetermined relation with respect to the valve seats thereof.

Another object is to provide a tool for accurately determining the position of a valve stem guide bushing to be removed from the cylinder block of an engine and for subsequently installing a new valve stem guide bushing in the same position.

Another object is to provide a simple and inexpensive tool of strong and durable construction for accurately installing valve stem guide bushings in the cylinder block of internal combustion engines or the like in an expeditious and highly efficient manner.

Other and further objects and advantages of the present invention will become apparent from the following description and drawings in which:

Fig. 1 is a side elevation of the tool of the present invention.

Fig. 2 is a longitudinal section of the tool shown in Fig. 1 taken along line 2—2 thereof; certain parts being shown in elevation.

Fig. 3 is a transverse section of the tool taken along line 3—3 of Fig. 2.

Fig. 4 is a bottom view of the tool shown in Fig. 1 taken along line 4—4 thereof.

Fig. 5 is a perspective view of the indicating or measuring bar of the present invention.

Fig. 6 is a view in reduced scale showing a cross section of a portion of the cylinder block of an engine with the tool of the present invention positioned thereon and in engagement with a valve stem guide bushing. The parts of the tool being shown in their final position with the valve stem guide bushing installed in place.

The tool of the present invention (Figs. 1, 2, and 3) comprises a hollow cylindrical barrel or sleeve 1 provided at its lower end with an externally threaded portion 3 of reduced diameter and a shoulder 4. Screwed upon the threaded portion 3 into firm engagement with the shoulder 4 is an internally threaded seat 6 having a spherical or convex lower surface 7. The lowermost end 8 of the sleeve 2 is also of spherical or convex configuration and forms a continuation of the spherical surface 7 of the seat 6.

2

Slidably disposed within the sleeve 2 is a plunger or driver 9 provided with a plurality of annular grooves 10, 11, and 12. The upper end of the driver 9 is provided with an enlarged head 13 forming an integral portion thereof while the lower end of the driver is provided with a removable cylindrical tip 14 of the same diameter as the driver 9. The tip 14 is provided with a threaded portion 15 of reduced diameter which is screwed into an internally threaded bore 16 in the lower end of the driver 9 to thereby firmly secure the tip to the same. The lower end of the tip 14 comprises a flat bottom surface 17 provided with a cylindrical pin or guide 18 at the center thereof.

The upper end of the sleeve 1 is provided with an elongated groove 19 within which an indicating or measuring bar 20 is slidably disposed. The measuring bar 20 is provided with an elongated slot 21 while a lock-screw 22 provided with a large head 23 extends through the slot 21 of the bar 20 in the groove 19 and is threadedly secured to the sleeve 1. The upper end of the bar 20 is bent inwardly into proximity of the driver 9 to form a pointer 24, as best seen in Fig. 2.

The sleeve 1, driver 9, and seat 6 are preferably made from chrome nickel steel while the tip 14 is preferably made from brass or similar soft material.

The driver 9 is loosely fitted in the sleeve 1 so that it freely slides therein without lateral play. The diameter of the driver 9 and tip 14 is of such size that the driver may be freely inserted into the valve seat opening of an internal combustion engine and the seat 6 of the sleeve 1 is of such size as to properly fit into and seat on the valve seat of the cylinder block.

In use the tool is placed with the seat 6 upon the valve seat 25 (Fig. 6) of the cylinder block 26 of the engine and the driver 9 is lowered so that the guide 18 enters the bore 27 of the valve guide bushing 28 and the flat bottom surface 17 of the tip rests on the upper end 29 of the bushing. Thereupon, the thumb screw 22 is loosened and the indicator bar 20 is shifted relative to the sleeve 1 until the upper end or pointer 24 of the bar is in accurate alignment with one of the annular grooves or indicating lines for instance line 10 (Fig. 6) and the bar 20 is firmly locked in this position by tightening the thumb screw 22. The tool is now in the position shown in Fig. 6. The above measuring procedure accurately determines the position of the valve stem guide sleeve 28, which is to be replaced, with respect to the valve seat 25 of the cylinder block 26.

The tool is now removed from the cylinder block 26 of the engine and the old guide bushing 28 is removed in any conventional manner from the bore 30 in the cylinder block 26. A new valve stem guide bushing 28 is now partially inserted in the bore 30 and the tool is thereupon placed in position on the cylinder block 26, i. e., with its seat 6 upon the valve seat 25, without disturbing the setting of the measuring bar 20. The guide pin 18 is inserted into the bore 27 of valve stem guide bushing and the bottom face 17 of the tip 14 of the driver is placed upon the upper end 29 of the new bushing 28. Thereupon while the operator holds the sleeve 1 in vertical position with the seat 6 of the sleeve in firm position on the valve seat 25, the head 13 of the driver 9 is tapped with a hammer and the new valve stem guide bushing 28 is driven home into the bore 30 in the cylinder block of the engine until the pointer 24 of the bar 20 is in registration with the annular groove or mark 10 on the driver 9, as shown in Fig. 6. The new valve stem guide bushing 28 is now accurately installed in the same position as the old bushing and the tool is removed.

The spherical or convex configuration of the seat 6 of the sleeve 1 assures an accurate seating of the tool on the valve seat 25 of the cylinder block 26 and due to this convex configuration the seat 6 fits all inlet or exhaust valve seats of any degree of inclination. Consequently, the tool is universally adaptable for all internal combustion engines.

The guide pin 17 functions not only to accurately center the tool relative to the bushing 28 but also prevents fouling of the bushing by the tip 14 of the driver. The tip 14 may be unscrewed and readily removed from the driver and other tips provided with guide pins of different diameters and/or length may be employed for bushings with bores of different size.

The measuring bar 20 or the bottom face of the groove 19 (Fig. 1) may be provided with indicating lines 32 or 33, respectively, calibrated for inserting the valve stem guide bushings for various types of engines so that no initial measuring operation to determine the position of the old bushing, as hereinbefore described, is necessary. When indicating lines on the bar 20 such as shown at 32 are employed, they are preferably used by aligning the respective line 32 with the upper edge 34 of the sleeve 1. However, when indicating lines 33 on the bottom face of the groove 19 are used, then the lowermost edge 35 of the bar 20 is aligned with the respective indicating line 33, to obtain the desired setting of the bar 20 with respect to the sleeve 1.

Depending upon the spacing of the upper end 29 of the valve stem guide bushing 28 from the valve seat 25 of the engine block the upper end or pointer 24 of the measuring bar 20 may be aligned with either one of the annular grooves or indicating lines 10, 11, 12 of the driver 9. In other words, depending upon the telescoping relation between the sleeve 1 and driver 9 the pointer 24 may be aligned with any one of the indicating lines 10, 11 or 12 during the measuring operation and subsequent insertion of the valve stem guide bushing as will be obvious to those skilled in the art.

It will be further apparent from the above that the seat 6 may be removed from the sleeve 1 and replaced with a new seat, if necessary, and, if desired, seats of different size and con-

figuration may be attached to the sleeve 1 as the conditions of practice may require.

I desire it to be understood that the invention is not limited to the particular application or precise details of construction illustrated, but that various applications, modifications, and variations may be resorted to without departing from the spirit or scope of the invention, and I deem myself entitled to all such applications, modifications, and variations as come within the scope of the claims appended hereto.

Having thus described my invention, what I claim as new and desire to protect by Letters Patent is:

1. A tool for installing valve stem guide bushings in the cylinder block of internal combustion engines comprising a sleeve having a seat adapted to be seated on the valve seat of the cylinder block, a driver having an indicating line slidably disposed in said sleeve and adapted to engage with its bottom surface the upper end of a valve stem guide bushing partially inserted in the cylinder block below the valve seat thereof, indicating means adjustably mounted on said sleeve, and means for locking said indicating means in predetermined position relative to said sleeve, whereby when said driver is tapped at the free end thereof the valve stem guide bushing may be driven home in said cylinder block into predetermined position indicated upon registration of said indicating means with the indicating line on the driver.

2. A tool for installing valve stem guide bushings in the cylinder block of internal combustion engines comprising a sleeve having a spherical seat adapted to be seated on the valve seat of the cylinder block, a driver having an indicating line at its periphery slidably disposed in said sleeve and adapted to engage with its bottom surface the upper end of a valve stem guide bushing partially inserted in the cylinder block below the valve seat thereof, an indicator adjustably mounted on said sleeve and having a pointer disposed above said sleeve and projecting into proximity of said driver, and means for locking said indicator in predetermined position relative to said sleeve, whereby when said driver is tapped at the free end thereof the valve stem guide bushing may be driven home in said cylinder block into predetermined position indicated upon registration of the pointer of said indicator with the indicating line on the driver.

3. A tool for installing valve stem guide bushings in the cylinder block of internal combustion engines comprising a cylindrical barrel, a seat having a convex bottom surface removably secured to the lower end of said barrel, a cylindrical driver provided with an indicating mark and slidably mounted in said barrel, said driver being provided with an enlarged head at the upper end thereof, a tip removably secured to the lower end of said driver and provided with a guide pin, a measuring bar adjustably secured to said barrel and including a pointer extending into proximity of the driver above said barrel, and means for locking said measuring bar in predetermined position relative to said barrel, whereby when said driver is placed with the tip upon the upper end of a partially inserted valve stem guide bushing and the guide pin disposed within the bore thereof while the barrel is positioned with its seat upon the valve seat of the cylinder block the valve stem guide bushing is driven home in said cylinder block into predetermined position relative to the valve seat thereof by tap-

ping the head of the driver until the mark on the driver is in registration with the pointer of said measuring bar.

4. A tool for installing valve stem guide bushings in the cylinder block of internal combustion engines or the like comprising a hollow cylinder having a seat adapted to engage a valve seat of the cylinder block, a cylindrical driver axially slid able within said hollow cylinder and adapted to engage with its lower end the upper end of a valve stem guide bushing partially inserted in the cylinder block below said valve seat, an indicator adjustably mounted on said hollow cylinder and projecting into proximity of said driver, and a mark on said driver, whereby upon tapping of the upper end of the driver the valve stem guide bushing is driven home into predetermined position relative to the valve seat as indicated upon registration of the indicator with said mark.

5. A tool for installing valve stem guide bushings in the cylinder block of internal combustion engines or the like comprising a hollow cylinder having a convex seat at its lower end adapted to engage a valve seat of the cylinder block, a cylindrical driver axially slid able within said hollow cylinder and having a removable tip at its lower end provided with a guide pin in axial alignment with said driver, said tip being

adapted to engage the upper end of a valve stem guide bushing partially inserted in the cylinder block below the valve seat thereof with the guide pin disposed within the bore of the bushing, an indicating member slidably mounted on said hollow cylinder for movement parallel thereto and having a pointer projecting into proximity of the driver above the upper end of the hollow cylinder, and means for locking said indicating member in predetermined positions on said hollow cylinder, said driver being provided with a mark adjacent its upper end whereby upon tapping of the upper end of the driver the valve stem guide bushing is driven home into predetermined position relative to the cylinder block indicated upon registration of the pointer with said mark.
